UNITED STATES PATENT OFFICE.

ERIK ANTON RUNDLÖF, OF STOCKSUND, SWEDEN.

METHOD OF AND MEANS FOR OPERATING INTERNAL-COMBUSTION ENGINES AND THE LIKE.

1,220,893.

Specification of Letters Patent. Patented Mar. 27, 1917.

Application filed February 9, 1914. Serial No. 817,474.

To all whom it may concern:

Be it known that I, ERIK ANTON RUNDLÖF, a subject of the King of Sweden, residing at Stocksund, in the Kingdom of Sweden, have invented new and useful Improvements in Methods of and Means for Operating Internal-Combustion Engines and the like, of which the following is a specification, reference being had to the drawing accompanying and forming a part hereof.

The method of operating internal combustion engines forming the object of this invention is distinguished from previously known methods concerning that part of the operation of the engine which involves the introduction of air into the same. As well known, the air is used besides for the combustion, partly for diffusing the fuel and for mixing with the gasified fuel for the purpose of producing the gas mixture, and partly for the cleaning of the combustion chamber of the engine. In all previously known operating methods the injection of air for these purposes takes place periodically in such a manner that the air passing through one or more inlet openings is always completely shut off from the engine one or more times during each cycle, usually during the greater part of the compression and expansion strokes.

The present invention is characterized by that during the operation of the engine, one or more jets of air are continually or nearly continually admitted into the engine and preferably into its combustion chamber, which jet or jets are either used exclusively for the cleaning or for the air circulation in the combustion chamber, or for both these purposes, or they are utilized during one part of the cycle for diffusing and mixing with the liquid or gasified fuel or other fluid and during the other part of the cycle for expulsion of the burned gas "scavenging" or for air circulation in the combustion chamber, or for both.

The air is preferably admitted under a pressure greater than the explosion pressure, so that the jet of air should not be interrupted during any time of the cycle of action of the engine. The advantages of this method are in the first place that the longest time possible is obtained for the "scavenging" of the combustion chamber and thereby also an as thorough "scavenging" as possible, and, secondly, that the air

or the gas-mixture is kept in constant circulation. The pressure, under which the air is admitted may, however, be less than the highest pressure arising in the cylinder, on account of which the air will be kept back during this short pressure period.

In consequence of the air being introduced in this manner the expulsion of the burned gas from the combustion chamber into the cylinder may even commence before the burned gas can leave the cylinder, and continue as long as the pressure in the cylinder is less than the air pressure. Consequently it is not necessary, as in previously known two-cycle engines to postpone the "scavenging" until the end of the stroke of the piston, then only to take place during an extremely short moment.

The invention is exemplified in the accompanying drawing, which shows in diagram a section of an engine arranged according to the invention.

1 denotes the cylinder, 2 the combustion chamber, 3 the piston, and 4 the exhaust pipe for the burned gas of an internal combustion engine. In the upper part of the combustion chamber 2 is secured the air inlet 5, which is so arranged that it may be kept open as long as the engine is running. Consequently, the air, which in suitable manner is kept under pressure, is admitted in a continual or nearly continual jet into the combustion chamber 2. From the aforesaid it will be readily understood that the "scavenging" takes place during a considerably longer time than when the piston, as is usually the case, has to come down near to the end of its stroke in order to lay open the comparatively small air-inlet 6, which in known manner leads from the crank-case of the engine, utilized as compression chamber. Moreover, the admission of air, according to the invention, commences in the combustion chamber proper, and, consequently, the "scavenging" will be most effective at just that point where it is most desired.

In addition to the aforesaid the advantage is also attained that during forced running, when the walls of the combustion chamber become very heated, the jet of air may be regulated by means of a valve, and by increasing the quantity of air admitted a corresponding cooling of the walls may be attained, simultaneously as more air is ob-

tained for the expulsion of the burned gas, which is on such occasion developed in great quantities.

The invention also comprises this arrangement that the fuel inlet, which in the drawing is indicated by the conduit 7, is located so that the fuel is injected into the air-jet in immediate proximity to the nozzle of the air-inlet. The fuel, or some other liquid, is 10 periodically injected in usual manner during each cycle, and during this injection the air and the fuel jets meet each other, so that the air acts diffusively on the fuel and becomes mixed with the same. When the 15 fuel injection has ceased the air only flows in, continually or nearly continually, and performs the "scavenging" in the aforesaid manner.

In the case related above that the pressure 20 under which the air is injected is less than the maximum pressure in the cylinder, the air conduit may suitably be provided with a back valve in order to prevent the gases from entering the air conduit.

Having now fully described my invention and the manner in which it is to be performed what I claim and desire to secure by Letters Patent is:—

1. The method of operating internal combustion engines and the like consisting in introducing fuel into and causing the same to ignite in the engine at intervals, and in admitting during the operation of the engine an approximately continual jet of air 35 into the engine, substantially as and for the purpose set forth.

2. The method of operating internal combustion engines and the like consisting in introducing fuel into and causing the same 40 to ignite in the engine at intervals, and in admitting approximately continually during the operation of the engine a jet of air into the combustion chamber of the engine, said jet of air being utilized for the "scavenging" 45 of the combustion chamber, substantially as described.

3. The method of operating internal combustion engines and the like consisting in introducing fuel into and causing the same 50 to ignite in the engine at intervals, and in admitting approximately continually during the operation of the engine a jet of air into the combustion chamber of the engine, said jet of air being utilized for causing circula-

tion of air in the combustion chamber and in 55 the cylinder of the engine, substantially as described.

4. The method of operating internal combustion engines and the like consisting in introducing fuel into and causing the same 60 to ignite in the engine at intervals, and in admitting approximately continually during the operation of the engine a jet of air into the combustion chamber of the engine, said jet of air being utilized during one part of 65 the cycle of action of the engine for diffusing and for mixing with the fuel, and during the other part of the cycle of action of the engine for "scavenging" and for causing circulation of air in the combustion chamber 70 and in the cylinder of the engine, substantially as and for the purpose set forth.

5. The method of operating internal combustion engines and the like consisting in introducing fuel into and causing the same 75 to ignite in the engine at intervals, and in admitting during the operation of the engine an approximately continual jet of air into the engine, for the purpose of "scavenging" 80 the combustion chamber, or causing circulation of air in the combustion chamber, or in the cylinder of the engine, or for diffusing and mixing with the fuel, or other liquid, during a part of the cycle of action of the engine and "scavenging" or causing 85 circulation of air in the combustion chamber or in the cylinder of the engine during the other part of the cycle of action of the engine, substantially as described.

6. In an internal combustion engine the 90 combination with a combustion chamber, of means for admitting a practically continual jet of air into the said chamber substantially as and for the purpose set forth.

7. In an internal combustion engine, the 95 combination with a combustion chamber, of means for admitting a practically continual jet of air into the said chamber and means for admitting fuel into the said chamber in the way of the jet of air and in close proximity to the means for admitting the air, for the purpose of diffusing the fuel by means of and mixing the same with the air, 100 substantially as described.
